(57) **CLAIM**

We claim the ornamental design for a blender, as shown and described.

DESCRIPTION

FIG. 1 is a front perspective view of a blender showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1; and,

FIG. 9 is an enlarged view of the encircled portion in FIG. 1.

The evenly dashed broken lines in the figures depict portions of the blender which form no part of the claimed design. The dot-dash broken lines encircling portions of the claimed design that are illustrated in enlargements form no part of the claimed design.
